Primary Examiner — Natasha Vujcic*Assistant Examiner* — Gilbert B Ford(74) *Attorney, Agent, or Firm* — Christopher A. Rothe; Culhane Meadows, PLLC(57) **CLAIM**

We claim, the ornamental design for a plunger body for syringe, as shown and described.

DESCRIPTION

FIG. 1 is a perspective view of a plunger body for syringe; FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines depict portions of the plunger body for syringe that form no part of the claimed design.
